US00D776184S

(12) **United States Design Patent** (10) Patent No.: **US D776,184 S**
(45) Date of Patent: ** Jan. 10, 2017

(54) **CAMERA**

(71) Applicant: **Sony Corporation**, Tokyo (JP)

(72) Inventors: **Takahiro Tsuge**, Tokyo (JP); **Takeshi Miyazaki**, Tokyo (JP); **Yasuhiro Okabe**, Kanagawa (JP); **Yuji Kawasaki**, Tokyo (JP); **Osamu Toyoshima**, Tokyo (JP); **Osamu Mizukami**, Kanagawa (JP); **Yuuji Sasaki**, Tokyo (JP); **Kazuhiro Nishida**, Tokyo (JP); **Yutaka Usui**, Saitama (JP)

(73) Assignee: **Sony Corporation**, Tokyo (JP)

(**) Term: **14 Years**

(21) Appl. No.: **29/495,800**

(22) Filed: **Jul. 3, 2014**

CLAIM

The ornamental design for a camera, as shown and described.

DESCRIPTION

FIG. 1 is a front, top and right side perspective view of a camera showing our new design;

FIG. 2 is a front elevational view thereof;

FIG. 3 is a rear elevational view thereof;

FIG. 4 is a right side elevational view thereof;

FIG. 5 is a top plan view thereof;

FIG. 6 is a bottom plan view thereof; and,

(Continued)

FIG. 7 is an enlarged perspective view along the lines 7-7 and 7-7' of FIG. 1.

The broken lines indicate the unclaimed portions of the camera and form no part of the claimed design.

1 Claim, 7 Drawing Sheets
